UNITED STATES PATENT OFFICE.

JOSEPH R. SHOWERS, OF SHELBYVILLE, INDIANA.

UNIVERSAL CASH-DRAWER REGISTER AND REWIND APPARATUS.

Application filed August 1, 1924. Serial No. 729,476.

To all whom it may concern:

Be it known that I, JOSEPH R. SHOWERS, a citizen of the United States, and a resident of Shelbyville, county of Shelby and State 5 of Indiana, have invented a certain new and useful Universal Cash-Drawer Register and Rewind Apparatus; and I do hereby declare that the following is a full, clear, and exact description thereof, reference being had to 10 the accompanying drawings, in which like numerals refer to like parts.

This invention relates to a cash drawer cabinet adapted to serve as a support or stand for any one of a number of standard 15 commercial registers otherwise known as adding machines and to a rewind attachment.

The chief object of the invention is to associate the drawer releasing mechanism and 20 the rewind attachment with any one of a number of makes of a standard adding machine or register whereby one cash drawer outfit as a unit is readily adapted to any one standard adding machine.

25 The chief features of the invention consist in the complete adjustability of the drawer releasing mechanism and the rewind mechanism of a cabinet to any standard form of adding machine.

30 The full nature of the invention will be understood from the accompanying drawings and the following description and claims:

Fig. 1 is a side elevational view of an 35 adding machine, a cash drawer cabinet including a releasing mechanism and a rewind mechanism and support, parts being shown in section to show other parts in detail. Fig. 2 is a rear elevational view of the same. 40 Fig. 3 is a top plan view of the rewind mechanism, parts being shown in section to illustrate other parts in detail.

In the drawings 10 indicates a cabinet containing a compartment 11 adapted to receive a cash drawer 12. Said cash drawer supports a spring 13, seatable when in compressed relation in a bearing plate 14 secured to the cabinet. The top of the cabinet is herein indicated by the numeral 15 and is 45 apertured as indicated at 16. A lever pivotally supported at 17 has an offset portion 18 and a drawer engaging portion 19. When the lever is tripped the drawer 12 is released from the locking portion 19 and under 50 the influence of spring 13 is projected outwardly. A suitable bell mechanism may

also be adapted to be rung when the drawer is released.

In Fig. 1 there is illustrated one form of a Burroughs adding machine or register. 60 Herein the same is indicated by the numeral 20. This machine carries a shaft 21 associated with which is exteriorly positioned an actuating arm 22 terminating in a handle if desired. The actuating mechanism herein disclosed is adapted to engage a lateral member 23, carried by an arm 24 radially adjustable upon a bracket 25 in turn longitudinally adjustable upon the slotted portion 26 of the lever previously described. 65 By means of the securing member 27, the arm 24 may be adjusted not only radially but also angularly to the bracket 25 and in the plane including the same. All of said parts are secured together in rigid but adjusted relation so that when the handle 22 is in the lower-most position as shown in Fig. 1 the lever is depressed, which permits the drawer to be released and opened by the spring. A suitable end bracket 28 is 70 adapted to enclose the free end of the slotted extension 26 and limit the latching movement of the lever.

As shown clearly in Fig. 1 by the dotted lines the arm 24 may be readily and rigidly 75 adjusted to the exterior operating member or handle of substantially all of the present commercial types of adding machines, provided, however, that the adding machine is positioned so that the exterior operating 80 member or handle lies in substantially the same plane as the lateral portion 23 so that said portion may be engaged by said exterior operating member. Thus the cabinet 85 10 must be of a considerable width so as to 90 accommodate the several adding machines 95 which vary in width.

Heretofore rewind apparatus has been utilized for rewind purposes in specific instances and in some instances has been constructed so as to be readily attachable to or detachable from a specific register or adding machine such as a short-hand machine and the like. Heretofore, however, there has never been a rewind attachment universally 100 adjustable to any one of substantially all of the commercial types and makes of adding machines or registers whether having the standard or extra width platens.

One advantage of the rewind device independent of the adjustability herein disclosed, is that among many other things it

enables the operator of the adding machine to keep an itemized record of the day's sales as well as a totalized record of each sale. Thru the use of carbon paper or carbon-backed multiple rolls the record of each sale may be supplied to the customer and the other or carbon record retained by the rewind. The resultant construction, therefore, is a complete transformation of substantially any one of the present commercial types or makes of adding machines into a recording cash register at a relatively low cost. The invention herein disclosed, therefore, permits the present owners of adding machines to secure recording cash register service therefrom at a nominal cost and also brings the cash register into direct competition with the recording and non-recording adding machines.

20 As shown clearly in Figs. 1 and 2 the cabinet 10 supports a pair of bolts 30 and a U-shaped bracket 31 having the connecting portion 32, shown provided with a pair of aligned elongated slots 33. These slots are 25 adapted to receive the bolts 30 and by means of the wing nuts 31 said bracket can be adjusted with respect to the cabinet 10 and the register.

20 The U-shaped standard 31 is provided with two transverse connecting portions 34 and 35. Upon each of the standards there is slidably mounted a bracket 36 having the grooves 37 therein adapted to receive the standard 31. Near the top of each of the 35 standards there is mounted a screw bolt 137 and associated therewith is a washer 38 and a wing nut 39. The bracket 36 also carries a screw bolt 40 with which is associated a washer 41 and a wing nut 42.

40 As shown most clearly in Fig. 1 an L-shaped bar 43 includes an L-shaped slot 44 having an arcuate or curved portion 45 intermediate the angular portions of the slots and connecting the same. The 45 continuous slot 44-45 is of sufficient width to receive the bolts 137 and 40 as shown in the aforementioned figures. Therefore, when the wing nuts 42 and 39 are released the bracket 36 may be slid longitudinally 50 upon the standard 31 and at the same time the angular member or extension 43 can be adjusted substantially universally about the stationary pivot 37 thru the two left-hand quadrants, reference being had to Fig. 1.

55 The free end of the angular portion of the member 43 is provided with an opening 46 and axially slidably and rotatively supported in said bearing is a shaft 47. It will be understood (see Figs. 2 and 3) that a pair 60 of angular members 43 are provided and thus the shaft 47 is supported in two bearings. The shaft 47 carries upon one end a hand or thumb wheel 48. The shaft 47 carries suitable mechanism for receiving the 65 paper removed from the roll 49 upon the

register 20 and is adapted to rewind the discharge paper therefrom.

As shown clearly in Fig. 1 the several circles indicate the paper roll positions in the several makes of commercial adding machines or registers. Other circles suitably legended indicate suggested rewind positions. Herein a Burroughs register is illustrated and to show that the suggested rewind positions are purely arbitrary and can be varied to suit the ideas of the purchaser, the rewind position herein disclosed associated with the Burroughs roll 49 is positioned for one position that coincides with the suggested position for the Victor rewind roll.

Reference will now be had particularly to Figs. 2 and 3 wherein the particular rewind mechanism is illustrated in detail. Any desired rewind mechanism, however, may be substituted in the broader features of the invention for that hereinafter described. A sleeve 50 carries a pair of plates 51, which act as guides for the paper rewound in roll formation upon sleeve 50. The sleeve 50 is extended at 52 and a set screw or other means 53 is adapted to adjustably position the rewind roll support upon rewind shaft 47 and longitudinal thereof and connects said roll support and shaft together for simultaneous operation. Adjacent the opposite end of the sleeve 50 there is shown a clutch face 54 rigidly but adjustably secured to the shaft 47, and a complementary clutch 55 is rotatively mounted upon the shaft 47. The clutch member 55 also carries a sprocket wheel 56 and said sprocket wheel 56 carries a sprocket chain 57 that is adapted to mesh with a similar sprocket wheel not shown but mounted upon the platen shaft of the register or adding machine. A spring 157 is concentric with the shaft 47 and bears upon the sprocket wheel 56 and the tension of this spring is adjusted by means of the collar 58 secured to the shaft.

By the foregoing construction it will be understood that the position of the gearing or drive may be longitudinally adjusted with respect to the shaft 47 so as to be in alignment with the sprocket wheel mounted upon the platen shaft or upon a stub shaft associated with a platen shaft. In some machines the sprocket wheel 56 is positioned to the right of the rewind roll and for other machines it is positioned to the left, while in still other machines it is positioned out beyond that portion of the shaft supported between the two bearings. It also may be necessary to mount the rewind roll at either end of the rewind shaft instead of intermediate the standards. Complete adjustability so far as positioning is concerned is secured which will readily adapt the rewind mechanism herein described to any width of carriage or platen and any available position of the platen supported sprocket and

the only available position is determinable by the adding machine position, determinable initially by the cooperation of arm 22 with lateral extension 23 of the cash drawer releasing mechanism.

5 The invention claimed is:

1. The combination of a support for a standard register, comprising a cabinet including a register position determining mechanism, and a rewind device support supported by said cabinet and relatively adjustable to the register positioned upon said cabinet for operatively associating a rewind device with the cabinet-supported, predetermined-positioned register.

10 2. A device of the character defined by claim 1 characterized by the register position determining mechanism being relatively

fixed and the rewind device support being adjustable upon said cabinet. 20

3. A device of the character defined by claim 1 characterized by the rewind device support adjustably supporting a rewind mechanism.

4. A device of the character defined by claim 1 characterized by the register position determining mechanism being relatively fixed and the rewind device support being adjustable upon said cabinet and in addition 25 adjustably supporting the rewind mechanism lateral to the adjustable mounting of the rewind device support upon the cabinet. 30

In witness whereof, I have hereunto affixed my signature.

JOSEPH R. SHOWERS.
